PRODUCTION OF NAPHTHALENE

James R. Calkins, Media, Pa., assignor to Sun Oil Company, Philadelphia, Pa., a corporation of New Jersey
No Drawing. Filed Apr. 29, 1960, Ser. No. 25,531

6 Claims. (Cl. 260—672)

This application is a continuation-in-part of my pending application, Serial No. 671,731, filed July 15, 1957, now abandoned.

This invention relates to the preparation of naphthalene from hydrocarbon stocks. It particularly relates to the method of producing naphthalene from petroleum fractions containing alkylnaphthalenes in admixture with other aromatic and/or non-aromatic hydrocarbons.

Petroleum fractions which boil within the range of 400—550° F. generally contain substantial amounts of alkylnaphthalenes, such as mono-, di-, and tri-methyl-naphthalenes and in smaller quantity, the ethylnaphthalenes. Recycle fractions, which are formed in the cracking of petroleum stocks and which include this boiling range, often contain major proportions of aromatic hydrocarbons that are mainly alkylnaphthalenes. Such fractions typically may have aromatic contents varying within the range of 25—97% but usually contain between 50% and 95% aromatics depending upon the particular operation in which the petroleum fractions are produced. These hydrocarbon charge stocks are obtained in both catalytic and thermal cracking processes and in operations in which combinations of catalytic and thermal cracking steps are utilized. Stocks having high alkyl-naphthalene contents can also be obtained by extracting straight run petroleum fractions of appropriate boiling ranges, such as kerosene, or catalytic fractions such as catalytic gas oil, with solvents, such as furfural or sulfur dioxide, or by selective adsorption with silica gel. These aromatic concentrates may contain 100% aromatic hydrocarbons.

The present invention is directed to the use of hydrocarbon charge stocks of the type referred to above for the preparation of naphthalene in high concentration. The charge stock used in practicing the invention is a hydrocarbon fraction boiling substantially within the range of 400—550° F. but more preferably between 450—550° F. and composed by weight of 35—100% aromatic hydrocarbons including substituted condensed ring aromatics such as alkylnaphthalenes and from 65—0% non-aromatic hydrocarbons. This charge material also commonly contains substantial amounts of sulfur compounds that normally occur within this boiling range. Charge stocks most typically employed have an aromatic content within the range of 50—95% by weight. In general, the substituted condensed ring aromatics constitute about 20% to 80% of the total aromatic hydrocarbons present in the charge stock.

It has been proposed heretofore to make naphthalene by subjecting stocks of this kind to thermal hydrodealkylation in a single stage at a high temperature in excess of 1300° F. However, this procedure has not proved to be satisfactory for commercial practice for stocks containing substantial amounts of non-aromatic hydrocarbons, for the reason that a highly exothermic reaction occurs that causes the temperature to rise sharply above the level that can be tolerated safely in plant operation. In fact, with charge stocks containing only 10% non-aromatic hydrocarbons, it has been found that the exothermic heat of reaction from removing substantially all of the side chains from the aromatic rings and the addition of hydrogen to form the dealkylated aromatic ring and resultant paraffin product amounts to approximately 500 B.t.u. per pound of liquid feed. Further, it has been

2

found that when a temperature of about 1125° F. is reached, the hydrocracking of the non-aromatic components begins to take place at such a rate that a rapid temperature rise occurs, with the result that the overall hydrocracking reaction takes place progressively faster and the temperature becomes uncontrollable. In short, the reaction is designated as "runaway."

In addition, the dealkylation reaction, apart from the hydrocracking reaction, necessary to produce naphthalene from the above-described charge stocks is extremely exothermic. In some cases, the temperature rise due to the dealkylation reaction has been as much as 100° F. Therefore, the operating conditions of such a process, even with 100% aromatic content charge stocks, become difficult to control.

The present invention provides a method of making naphthalene from charge stocks as specified above wherein the temperature rise due to the hydrocracking of the non-aromatics and the dealkylation of the aromatics is minimized and controlled.

According to the invention, the charge material is first subjected to a conditioning treatment in the presence of a desulfurization catalyst and added hydrogen under conditions including a temperature within the range of 800—980° F., at which the non-aromatic components are converted to lower boiling compounds at a slow enough rate to prevent excessive temperature rise. Under these conditions, substantial conversion of the alkylnaphthalenes into naphthalene does not occur. In addition, a minor proportion of the aromatic hydrocarbons are at least partially hydrogenated. The conditioned reaction product from this first step is then subjected in a second step to a temperature above 1000° F., whereby dealkylation of the alkylnaphthalenes and dehydrogenation of the minor proportion of the aromatic hydrocarbons occurs. Due to the fact that the non-aromatic components have already been largely removed in the first reaction stage, the temperature in this second stage reaction does not rise excessively. Furthermore, those aromatic hydrocarbons which were hydrogenated in the first step are dehydrogenated in the second step thereby additionally aiding in the temperature control of the second step due to the endothermic nature of the dehydrogenation reaction. The final reaction product is fractionated to obtain naphthalene in high concentration.

Thus, the present invention is a two-stage process for making naphthalene from a hydrocarbon charge stock wherewith by removing the non-aromatics in the first stage and by regulating the temperature in the first stage to vary the degree of aromatic saturation, it is possible to control the temperature rise during the second stage. Further, better temperature control is realized in the first stage with charge stocks containing non-aromatics since the exothermic addition of hydrogen to the aromatic hydrocarbons and to the cleaved carbon-carbon bonds tends to counterbalance the endothermic cracking of the non-aromatic hydrocarbons. On the other hand, when charging 100% aromatic charge stocks, the exothermic addition of hydrogen to the aromatic hydrocarbons provides additional heat so that the desired first stage temperature can be obtained without excessive external heat requirements. In the second stage, the endothermic dehydrogenation of the hydrogenated aromatics from the first stage reaction at least partially counterbalances the exothermic dealkylation reaction of the alkylnaphthalenes thereby providing better temperature control.

The term "hydrocracking" is primarily defined as the cumulative result of cleaving, i.e. cracking, carbon-carbon bonds and of adding hydrogen to the cleaved bonds. The overall hydrocracking reaction is generally exothermic.

The term "dealkylation" is primarily defined as the cumulative result of removing the alkyl side chains from the substituted condensed ring aromatic hydrocarbons and of adding hydrogen to form the dealkylated condensed ring aromatic hydrocarbons. The overall dealkylation reaction is generally exothermic.

In this invention, the term "hydrocracking" will also include the hydrogenation of a minor proportion of the aromatic hydrocarbons and the term "dealkylation" will include the dehydrogenating of those aromatics hydro- 10 genated during "hydrocracking."

The critical feature of the first stage reaction is to condition the first stage product by balancing hydrogenation, cracking, and desulfurization in such a manner that the characteristics imparted thereto perform the function of aiding temperature control in the second stage. The balance between these reactions can be measured by a knowledge of hydrogen consumption and the dicyclic aromatic hydrogenation equilibrium relationship. For example, if the dicyclic aromatic is considered to be 20 naphthalene, then the equilibrium relationship for the reaction:

Temp., ° F.:	K=equilibrium constant
980	15.8
800	4,000

Thus, it is seen that at 300 p.s.i.g., by regulating the temperature of the reaction, the degree of hydrogenation of naphthalene can be varied. It is noted that substantial saturation occurs at 800° F. as evidenced by the high value of the equilibrium constant, K. On the other hand, at temperatures above 980° F., the K value would be extremely small indicating that very little hydrogenating was occurring. The equilibrium behavior for the mixed substituted naphthalenes derived from petroleum would show a similar temperature dependence.

The effect of hydrogen consumption and temperature on the catalytic treatment of an aromatic concentrate (boiling range 450-525° F.) from catalytic gas oil containing 0.58 wt. percent sulfur during the first stage conditioning step is illustrated as follows.

Example I

Operating conditions:

T=900° F.

P=500 p.s.i.g.

Space velocity=1

Hydrogen recycle—11,000 s.c.f./barrel

Catalyst: Co—Mo on alumina

Results:

Hydrogen consumption=300 s.c.f. barrel

Sulfur content of product=<0.01%

Since hydrogen consumption for sulfur removal alone would be expected to be about 65-75 s.c.f./barrel (standard cubic feet per barrel of feed) for each 1% S in the feed, it is seen that the hydrogen consumption of 300 s.c.f./barrel per 0.6% S in feed is about 5-10 times larger than that due to sulfur removal alone. The remainder of the hydrogen is used in partial ring saturation as would be predicted from the equilibrium relationship discussed hereinabove.

In a preferred embodiment of the invention, the first conditioning step is carried out in the presence of a catalyst and added hydrogen while the second step involves a thermal treatment to effect dealkylation of the alkynaphthalenes. The use of a catalyst in the first conditioning step facilitates hydrocracking of the non-aromatic hydrocarbons and permits the use of a lower reaction temperature. In addition, the presence of the catalyst is necessary if proper hydrogenating of a minor proportion of the aromatic hydrocarbons is to be obtained. At the same time, it effects desulfurization by converting sulfur

compounds in the charge stock to hydrogen sulfide. The naphthalene recovered from the final reaction product accordingly is substantially free of sulfur as a result of the use of the catalyst in the first conditioning step. Any of the catalysts which are known to be useful desulfurization catalysts are suitable for use in the conditioning step. For example, cobalt molybdate on alumina or molybdenum disulfide on alumina can be used in practicing the invention. The conditions for conducting the catalytic conditioning step include a temperature within the range of 800-980° F., a pressure of 150-1000 p.s.i.g., with a range of 200-500 p.s.i.g. preferred, a hydrogen to hydrocarbon mole ratio of 3:1 to 25:1 and preferably 5:1 to 15:1, and a liquid hourly space velocity of 0.2 to 10 (volumes of charge per hour per bulk volume of catalyst). The hydrogen consumption under these conditions should be between 65-500 s.c.f. per barrel of liquid feed per percent sulfur in the feed and preferably between 200 and 400 s.c.f./barrel. The conditions for the second stage thermal treatment include a pressure of 150-1000 p.s.i.g., preferably 200-500 p.s.i.g., a hydrogen to hydrocarbon mole ratio within the range of 3:1 to 25:1 and preferably 5:1 to 15:1, a residence time of 2-300 seconds with a preferred residence time of 10-60 seconds, and a temperature above 1000° F., preferably within the range of 1200-1400° F., sufficient to effect a dealkylation of the alkynaphthalenes while dehydrogenating the minor proportion of hydrogenated aromatic hydrocarbons.

A still further manner practicing the invention involves catalytically conditioning the charge under the conditions set forth for the embodiment first mentioned above and then catalytically dealkylating the alkynaphthalenes in the presence of a desulfurization catalyst. The presence of the catalyst in the latter step facilitates the dealkylation reaction and in some cases permits it to be carried out at a lower temperature than that required for thermal dealkylation. The catalyst also effects the conversion of any remaining sulfur into hydrogen sulfide and hence permits the preparation of naphthalene having negligible sulfur content. The conditions for the catalytic dealkylation step include a pressure of 150-1000 p.s.i.g. with a range of 200-500 p.s.i.g. preferred, a hydrogen to hydrocarbon mole ratio of 5:1 to 25:1, a liquid hourly space velocity of 0.2-5.0, and a temperature above 1000° F., usually between 1100° F. and 1200° F., sufficient to dealkylate the alkynaphthalenes, convert any remaining sulfur mainly into hydrogen sulfide and dehydrogenate the minor proportion of hydrogenated aromatic hydrocarbons.

In practicing any of the foregoing embodiments of the invention, the total reaction product from the first conditioning step can be charged to the second step. However, it is preferable to subject the first reaction product to distillation to obtain a fraction boiling mainly in the range of 400-550° F. for use as charge to the second step. This distillation removes material formed in the first hydrocracking reaction which boils below 400° F. and which will not contribute to the formation of naphthalene in the second reaction stage. It also removes a minor amount of polymeric material that boils above 550° F. which would tend to contribute to coke formation if allowed to remain in the charge to the second step.

In both the first and second reaction stages of each of the foregoing embodiments, coking occurs after a time to such extent that coke removal from the reaction zone is required. This can be done in conventional manner by passing an oxygen-containing gas through the reaction zone to burn out the coke. In the steps in which a desulfurizing catalyst is used, burning of coke from the catalyst restores its catalytic activity.

The following are examples of certain embodiments of the invention:

Example II

A charge stock was prepared by distilling a gas oil fraction obtained by a combination of catalytic and

thermal cracking operations. The charge stock had a boiling range of 460-500° F., an aromatic hydrocarbon content of 78% by weight, including about 1% naphthalene, and a sulfur content of 0.25%. Hydrogen was mixed with the charge in a mole ratio of 10:1 and the mixture was heated to 900° F. and fed in vapor phase into a catalytic hydrocracking zone at a pressure of 500 p.s.i.g. The catalyst was a cobalt molybdate on alumina desulfurizing catalyst containing 3% cobalt and 15% molybdenum. The liquid space velocity of the charge in the reaction zone was 1 vol./vol. of catalyst/hr. The reaction product contained 8.3% of C₅-400° F. fraction having an F-1 clear octane rating of 82.7 and 86.1% of material boiling above 400° F.

The 400° F.+ material was heated to 1200° F. in admixture with hydrogen in a mole ratio of hydrogen to hydrocarbon of 10:1 and the mixture was fed into a soaking zone. Pressure in the soaking zone was 200 p.s.i.g. and the residence time was 20 seconds. Reaction products from this thermal step were separated into the following fractions:

	Percent by weight
C ₄ and lighter hydrocarbons	37.0
C ₅ -400° F. fraction	15.0
400-450° F. fraction	23.0
450° F. and heavier	24.6

The 400-450° F. fraction was composed predominantly of naphthalene and had a freezing point of 78.6° C. and a sulfur content of 0.06%. The higher boiling fraction contained a small amount of naphthalene due to imperfect fractionation. Overall yield of naphthalene, based on the original charge stock was 23.7%.

Example III

The charge stock prepared as in Example II was subjected to a conventional thermal hydrodealkylation treatment, omitting the first conditioning step of the invention. The charge stock was admixed with hydrogen in a mole ratio of hydrogen to hydrocarbon of 10:1 under a pressure of 200 p.s.i.g. Heat was applied at a sufficient rate to raise the temperature of the mixture to 1300° F. But beginning at a temperature of about 1125° F., the temperature rose rapidly to above 1600° F. before the reaction could be stopped. This was a characteristic "runaway" reaction.

Example IV

A catalytic gas oil was solvent extracted with furfural to prepare aromatic concentrates of varying aromatic contents. These aromatic concentrates were first subjected to catalytic conditioning and then thermal dealkylation. The results, indicating temperature control characteristics, are as follows:

Sample	A	B	C	D
Aromatic Content	96.2	90.5	84.0	75.0
First Stage:				
Temp., ° F.	925	875	900	900
Press. p.s.i.g.	500	500	500	500
LHSV, v.v./hr.	0.86	1	1	1
Recycle gas rate, s.c.f./b.	3,000	7,750	5,060	10,850
Catalyst	Co-Mo	Co-Mo	Co-Mo	Co-Mo
Second Stage:				
Inlet Temp., ° F.	1,200	1,200	1,200	1,200
Max. Temp., ° F.	1,330	1,320	1,315	1,295
Press., p.s.i.g.	200	200	200	200
Residence Time, Sec.	12.7	12.5	13.2	13.3
Naphthalene yield, wt. percent of charge	31.8	23.3	21.8	22.8

The above data indicate the temperature control technique of the invention by varying the first step conditioning temperature. In comparison to Sample A, Sample B had a lower aromatic content and was processed at a lower temperature thereby hydrogenating the aromatics to a greater extent according to the equilibrium relationship. In addition, the lower temperature cracked less of the non-aromatics. Accordingly, the greater hydrogenation of Sample B with subsequent dehydrogenation in the

second step effectively counterbalanced the exothermic reactions of the second step. Sample A had less non-aromatics to crack and the higher temperature of the first step hydrogenated the aromatics to a lesser extent but cracked the non-aromatics to a greater extent. However, the temperature rise in the second stage was greater. Similarly, Samples C and D had 84% and 75% aromatic contents respectively and were conditioned at 900° F. Again, the exothermic reactions of the second step were effectively counterbalanced by the dehydrogenating of the first step hydrogenated aromatics.

Numerous modifications of the present invention will be obvious to those skilled in the present art without departing from the spirit of the invention. For example, the undalkylated alkylnaphthalenes can be recycled to the process to effect greater yields.

I claim:

1. A two-stage process for making naphthalene from a sulfur-containing petroleum fraction boiling mainly within the range of 400° F. to 550° F. and composed of at least 50% aromatic hydrocarbons comprising mainly alkylnaphthalenes and the remainder comprising mainly non-aromatic hydrocarbons which comprises subjecting said petroleum fraction to conditioning treatment in the presence of a desulfurization catalyst and added hydrogen under reaction conditions including a temperature between 800° and 980° F. and a pressure between 150 and 1000 p.s.i.g.; regulating the temperature, pressure, and amount of hydrogen added in said conditioning step to effect hydrogen consumption of from 65 to 500 standard cubic feet per percent sulfur in said petroleum fraction per barrel of said petroleum fraction to convert non-aromatic hydrocarbons to lower boiling compounds, to convert sulfur mainly to hydrogen sulfide, and to at least partially hydrogenate a minor proportion of the aromatic hydrocarbons without substantial conversion of the alkyl-naphthalenes to naphthalene; subjecting conditioned reaction product boiling mainly within the range of 400° F. to 550° F. to thermal treatment in the presence of added hydrogen at a pressure between 150 and 1000 p.s.i.g., a hydrogen to hydrocarbon mole ratio of from 3:1 to 25:1, a residence time of from 2 to 300 seconds, and a temperature above 1000° F. sufficient to effect dealkylation of alkylnaphthalenes and dehydrogenation of said hydrogenated aromatic hydrocarbons; and fractionating the final reaction product to recover naphthalene in high concentration.

2. A two-stage process according to claim 1 wherein said petroleum fraction is selected from the group consisting of aromatic concentrates separated from cracked gas-oil and aromatic concentrates separated from straight run petroleum fractions.

3. A two-stage process according to claim 2 wherein said petroleum fraction is an aromatic concentrate separated from cracked gas oil.

4. A two-stage process for making naphthalene from a sulfur-containing petroleum fraction boiling mainly within the range of 400° F. to 550° F. and composed of at least 50% aromatic hydrocarbons comprising mainly alkylnaphthalenes and the remainder comprising mainly non-aromatic hydrocarbons which comprises subjecting said petroleum fraction to conditioning treatment in the presence of a desulfurization catalyst and added hydrogen under reaction conditions including a temperature between 800° and 980° F. and a pressure between 150 and 1000 p.s.i.g.; regulating the temperature, pressure, and amount of hydrogen added in said conditioning step to effect hydrogen consumption of from 65 to 500 standard cubic feet per percent sulfur in said petroleum fraction per barrel of said petroleum fraction to convert non-aromatic hydrocarbons to lower boiling compounds, to convert sulfur mainly to hydrogen sulfide, and to at least partially hydrogenate a minor proportion of the aromatic hydrocarbons without substantial conversion of the alkyl-naphthalenes to naphthalene; subjecting conditioned re-

action product boiling mainly within the range of 400° F. to 550° F. to catalytic dealkylation in the presence of excess added hydrogen and a desulfurization catalyst at a pressure of between 150 and 1000 p.s.i.g., a hydrogen to hydrocarbon mole ratio of from 5:1 to 25:1, a liquid hourly space velocity of from 0.2 to 5.0, and a temperature above 1000° F. sufficient to dealkylate said alkyl-naphthalenes, to convert any remaining sulfur mainly into hydrogen sulfide, and to dehydrogenate said hydrogenated aromatic hydrocarbons; and fractionating the final reaction product to recover in high concentration naphthalene having low sulfur content.

5. A two-stage process according to claim 4 wherein said petroleum fraction is selected from the group consisting of aromatic concentrates separated from cracked gas oil and aromatic concentrates separated from straight run petroleum fractions.

6. A two-stage process according to claim 5 wherein said petroleum fraction is an aromatic concentrate separated from cracked gas oil.
